United States Patent Office

Des. 193,602
Patented Sept. 11, 1962

193,602

TIRE

Michael Tiborcz, 714 W. Market St., Akron, Ohio

Filed Mar. 14, 1961, Ser. No. 64,280

Term of patent 7 years

(Cl. D90—20)

FIG. 1

FIG. 3

FIG. 6

FIG. 2

FIG. 4

FIG. 5

FIG. 1 is a fragmentary perspective view of a tire showing my new design;

FIG. 2 is an enlarged plan view thereof;

FIG. 3 is an enlarged sectional view thereof taken on line 3—3 of FIG. 2;

FIG. 4 is an enlarged fragmentary elevational view of the side wall thereof; and

FIG. 5 is a fragmentary sectional view of the side wall thereof taken on the line 5—5 of FIG. 4;

FIG. 6 is a side elevational view of the tire on a reduced scale.

It is understood that the full-line portions are repeated throughout the entire circumference of the tire.

I claim:

The ornamental design for a tire, as shown and described.
